UNITED STATES PATENT OFFICE.

EDMONDO MICHELE BORGO, OF TURIN, ITALY.

INTERMITTENT STARTING DEVICE FOR INTERNAL-COMBUSTION MOTORS.

1,406,146.

Specification of Letters Patent. Patented Feb. 7, 1922.

Application filed February 25, 1920. Serial No. 361,206.

To all whom it may concern:

Be it known that I, EDMONDO MICHELE BORGO, a subject of the King of Italy, residing at Turin, Italy, have invented certain new and useful Improvements in Intermittent Starting Devices for Internal-Combustion Motors; and I do hereby declare the following to be a full, clear, and exact description of the invention, such as will enable others skilled in the art to which it appertains to make and use the same, reference being had to the accompanying drawing, and to letters or figures of reference marked thereon, which form a part of this specification.

The present invention has for its object an intermittent starting device for internal combustion motors, in particular for motors used in automobile vehicles in general. The device includes: an internal toothed member, connected directly or indirectly with the motor shaft, and intended to be rotated in one direction only and in an intermittent manner by an engaging pawl 20 yieldingly connected to and capable of oscillating on a driving shaft operated in opposition to the action of a return spring, by means of a pedal or handle. This driving shaft is placed parallel to the axis of 25 the internal toothed member but slightly eccentrically in respect to it, so that the engagement of the engaging pawl with the latter takes place for an angular amplitude of less than one complete rotation of the 30 driving shaft. In this starting device means, preferably yielding in character, are provided for stopping the driving shaft at the end of its return stroke in such a position that the engaging pawl is out of engagement from the teeth of the internal 35 toothed member.

A constructional form of this starting device is hereinafter described with reference to the annexed drawing to illustrate, 40 by way of example, the application to the motor of a motorcycle. It is obvious, however, that the said application is here described and illustrated only by way of explanation and is consequently not to be 45 taken as limiting the application of the invention.

In the said drawing: Fig. 1 gives a general view in side elevation of the application of the starting device to the motorcycle;— 50 Figures 2 and 3 show in detail views the

starting device in a longitudinal section and an end view respectively;—Figures 4 and 5 show the internal toothed member and the pawl in a transverse section on the line —3*—3* of Fig. 2 and in two different 60 working positions;—Figures 6, 6*, 7, 8, 9 are details.

In the example shown in the drawing the internal toothed member 1 intended to be operated by the engaging pawl 2 is connected indirectly with the shaft 3 of the motor arranged for instance longitudinally to the vehicle. In fact said member 1 is connected or in one piece with the counter shaft 4 of the change speed gear of the 70 vehicle located inside the motor casing 5 and receiving the movement from the main shaft 6 by means of the toothed wheel 7 engaging the teeth 8 milled on the outer side 75 of the member 1. The main shaft 6, which is provided externally with the sprocket 9 serving to drive, by means of a chain, the rear wheel 10 of the motorcycle, is driven in its turn by the shaft 3 of the motor by means of two bevel gears 11, 12 which are 80 connected to the said shaft 3 and wheel 7 respectively. The arrangement described above relating to the indirect connection of member 1 with the shaft 3 of the motor is quite peculiar to the example of application 85 represented in the drawing and may therefore vary according to the form and location in the vehicle of the motor to which the starting device is applied.

The element 1 (see Figs. 4 and 5) shows 90 internal teeth, preferably in the shape of a ratchet wheel in which the bottom 1' of each tooth is preferably rounded off in a broad curve, the tops 1'' being also slightly rounded off.

The engaging pawl 2 (see Fig. 8) is mounted, free to oscillate slightly, in a cavity 13 (see Fig. 6) of the head 14 of the driving shaft 15 after the insertion in the interior of said cavity of a flat spring 16 (see Fig. 9). This spring is suitably shaped to engage by its hook 16' over the terminal edge 14' of the head 14 provided with the cavity 13, and to bear partially against the inner walls 13', 13'' of said cavity, acting on the 100 outer walls of the pawl 2 in such a manner as to maintain the latter in a middle position, as illustrated by Fig. 4. The pawl 2 and the spring 16 are retained in the interior 105 of the cavity 13 by the flat head 17' of the 110

screw 17 (see Fig. 7) passing through the hole 2' of the pawl and screwed to the screw-threaded hole 14" of the head of the driving shaft 15.

5 The driving shaft 15 is mounted capable of rotating, in the interior of the support sleeve 18, which, by means of its flange 18', is fixed by means of screws 19, for instance, to the motor or change speed case 5 in such 10 a way that while the head 14 of the shaft with the pawl 2 is seen to be within the member 1, the axis —*x*. *x*— of the shaft 15 (see Fig. 2) is parallel to the axis —*y* *y*— of the member 1 but slightly eccentrically 15 disposed in respect to the latter, to a given amount —*e*—. The shaft 15 is provided at its outer end with the operating crank 20 having a jointed head or pedal capable of being brought to its position of rest as shown 20 by the dotted lines in Fig. 3. This head is formed by the rod 22 pivoted by the screw 21 to the head of the pedal and on which is mounted the sleeve 23 which is capable of turning, and is made preferably of aluminum, having a prismatic shape with, for instance, a triangular cross section, so as to make a good support for the foot by which the pedal is operated. If the starting device 25 is to be worked by the hand the shaft 15 may be provided with a handle equipped with a suitable grip.

The operation of this shaft 15 in the direction indicated by the arrows in Figs. 1 and 3, is effected opposite to the torsion spring 24, placed on the inner prolongation of the sleeve 18 and engaged with its ends in suitable holes milled in the head 14 of shaft 15 and in the flange 18' of sleeve 18 respectively. The shaft 15, brought back to 30 its normal position of rest by the spring 24, is held in this position by any stop means, for instance, by the pin 25 fixed to the flange 18' and against which the head 14 of the shaft rests. This pin, preferably elastic for the 35 purpose of absorbing the impact when the operating member returns to its position of rest, is formed by a spiral steel wire tightly wound upon itself.

The overhung end of the support sleeve 40 18, when the frame of the vehicle permits it, as is the case in the example represented, rests upon this frame with the object of obviating any breakage. Thus, in the example represented, the said end rests 45 on one of the longitudinal tubular bearers 26 of the frame of the motorcycle by means of the pair of adjusting wedges 27, 28 and is fastened to this point by the two stirrups 29, in half round wire, fixed to the cover 50 plate 30, bearing above on the sleeve 18 upon which bear the nuts 31 screwed to the jointed and screw-threaded ends of the said stirrups 29.

The working of the device is as follows: 55 In the rest position, that is when the head

14 of the shaft 15, forced by the spring 24 bears against the stop 25, the pawl 2 is in the position of Fig. 4 out of engagement from the internal toothed member 1.

By causing the pedal 20 to turn, in the direction of the arrows in Figs. 1 and 3, acting, for instance, with the foot on the sleeve or pedal 23, the pawl 2, owing to the eccentricity between the shaft 15 and the internal toothed member 1, is engaged with the teeth of the latter, as shown by the dotted lines in Fig. 4. The engagement of the end of the pawl 2 with the teeth of 1 may take place at once in an efficient manner at the bottom 1' of a tooth, or in an inefficient manner at the top 1" of a tooth. Even in the latter case breakages need not be feared for, owing to the spring mounting of the pawl 2 by means of the spring 16, the said pawl, by oscillating in either direction, slides 75 immediately to the bottom 1' of the corresponding tooth or of the one following and is brought finally to the efficient position of engagement marked in full lines in Fig. 5. Continuing then the movement of the pedal 20, the pawl 2, which after having pressed down the spring 16, rests completely on the shoulder 13' of the cavity 13, sets in rotation the member 1. After having accomplished a rotation of about 180° and owing 80 to the eccentricity between 15 and 1, the pawl 2 once more comes out of engagement with the teeth 1, as shown by dotted lines in Fig. 5. Releasing the pedal 20, it is acted upon by the spring 24, and returns to its initial position and with it returns also the pawl 2, which oscillating in the opposite direction to the shoulder 13" of the cavity 13, slides past the teeth of the member 1 which remains motionless, and returns to the initial position of Fig. 4. By repeating intermittently the action of the pedal in the direction of the arrows in Figs. 1 and 3, the element 1 is placed in intermittent rotation, and this latter through the toothed wheels 85 8, 7 and 12, 11, rotates the shaft 3 of the motor, which is thus started.

Once the starting is accomplished the member 1 rotates with the other parts of the motor and its teeth 1', 1" rotate freely out 90 of engagement from the pawl 2, which has returned meanwhile to its rest position as in Fig. 4.

In the example described above the internal toothed member and its pawl are 95 located in the change speed case 5 and this is very advantageous for the purpose of insuring a greater durability to the mechanism, but it is evident that these elements could just as well be placed freely on the outside. 100

I claim:

1. An engine starting mechanism, comprising an internally toothed ratchet wheel for the shaft for starting the motor, a starting crank shaft whose axis is off-set from 105

- the center of said wheel, and a pawl carried on said crank shaft for engagement with said ratchet teeth, whereby said pawl will travel in a path eccentric to the ratchet teeth to automatically engage and disengage said teeth. 5
2. An engine starting mechanism, comprising an internally toothed ratchet wheel for the shaft for starting the motor, the bases of the interdental spaces of said wheel being rounded, a crank-shaft whose axis is off-set from the axis of said wheel, and a pivoted pawl carried by said crank shaft for engagement with said teeth. 10
3. An engine starting mechanism comprising an internally toothed ratchet wheel for the shaft for starting the motor, the bases of the interdental spaces of said wheel being rounded and the ends of the teeth being rounded, a crank-shaft whose axis is off-set from the axis of said wheel, a head on said shaft having a pawl receiving recess, a pawl pivoted in said recess and limited in its movement by the walls of said recess. 15
4. An engine starting mechanism comprising an internally toothed ratchet wheel for the shaft for starting the motor, the bases of the interdental spaces of said wheel being rounded and the ends of the teeth being rounded, a crank shaft whose axis is off-set from the axis of said wheel, a head on said shaft having a recess therein, a pawl pivoted in said recess and a spring to hold said pawl in middle position in said recess. 35
5. An engine starting mechanism comprising an internally toothed ratchet wheel, a rotatable crank shaft, a head thereon, a pawl in said head arranged to engage said teeth during a partial revolution, a yielding stop for said head and a coil spring on said shaft to return the shaft to initial position and the head against said stop. 40
6. An engine starting mechanism comprising an internally toothed ratchet wheel, a rotatable crank shaft, a head thereon, a pawl in said head arranged to engage the teeth of said wheel for a partial rotation only, and a crank actuating member pivoted to the end of said crank to swing into 45 and out of operating position.
7. In a starting mechanism, a motor casing, an internally toothed starting ratchet wheel mounted therein, a flanged sleeve secured to said casing, a crank-shaft mounted in said sleeve whose axis is off-set from the axis of said wheel, a head on said shaft, a pawl pivoted in said head to engage the teeth of said wheel for a partial revolution, means to secure said sleeve to a vehicle 50 frame element, a spring stop and a spring to return the crank shaft to initial position with the head against said stop.
- In testimony that I claim the foregoing as my invention, I have signed my name.

EDMONDO MICHELE BORGO.
